WILLIAM A. CASWELL, OF PROVIDENCE, RHODE ISLAND.

Letters Patent No. 89,557, dated May 4, 1869.

IMPROVED BLIND-STOP.

The Schedule referred to in these Letters Patent and making part of the same.

To all whom it may concern:

Be it known that I, WILLIAM A. CASWELL, of the city and county of Providence, in the State of Rhode Island, have invented a certain new and useful Blind-Slat Fastener; and I do hereby declare the following specification, taken in connection with the drawings furnished, and forming a part of the same, to be a true, clear, and exact description thereof.

Figure 1 represents a front view of a window-blind, having one of my blind-slat fastenings attached.

Figure 2 represents the same in vertical section.

Like parts are lettered the same in each figure.

A represents the bottom rail of the blind.

B is the lower slat of the same.

C represents a curved finger, having slight notches cut upon the inside of the curve.

D is a circular plate, to which the finger is attached, near its lower end, by means of ears or lugs, projecting from the face of the plate, and a pin passing through them and the curved finger, and is shown at point marked E.

G is a spiral spring, fitted to a concave socket in the lower inside face of the finger C, and resting in a hole provided for it in the bottom rail of the blind.

By the outward pressure of the spring against the lower end of the curved finger, the upper end is forced against the upper edge of the lower slat, which is duly provided with a wire shoe, to prevent wear by friction.

H is a button or catch, riveted to the face of the plate D, and is so arranged, in relation to the finger C, that it can be turned into a slot, provided for the purpose, and prevent the moving of the finger, thus, in effect, bolting the blind-slat against intrusion from without.

The circular plate D is provided with countersunk holes, for the reception of screws, for fastening the same to the blind.

The operation of my fastening is obvious.

By contact with the upper edge of the slat, of the curved finger under pressure from the spring, the slat is retained in any desired position.

Having thus described my invention,

I claim as new, and desire to secure by Letters Patent—

1. The blind-slat fastener herein described, consisting of the curved finger C, the plate D, and spring G, or their mechanical equivalents, arranged and operating substantially as set forth, for the purposes specified.

2. In combination with the plate D, and finger C, the button H, constructed and operating substantially as described, for the purposes specified.

WM. A. CASWELL.

Witnesses:

HENRY MARTIN,
JOHN C. PURKIS.
